UNITED STATES PATENT OFFICE.

JOHN LAYTON GUERRANT, OF SEDALIA, MISSOURI.

FREIGHT-CAR DOOR.

Application filed November 22, 1920. Serial No. 425,782.

To all whom it may concern:

Be it known that I, JOHN L. GUERRANT, a citizen of the United States, residing at Sedalia, in the county of Pettis and State 5 of Missouri, have invented certain new and useful Improvements in Freight-Car Doors, of which the following is a specification, reference being had therein to the accompanying drawing.

10 This invention relates to grain car doors, especially although the improvements can be used on the doors of freight cars generally, it being the object of the invention to provide novel means for fitting and clamping the 15 main car door to the door frame to provide a tight fit or joint for preventing the grain or other contents from leaking past the door, without the necessity of using an inner grain door as customary, and this feature is also 20 useful for excluding dust, dirt, rain, air, and the like, from the contents of the car.

Another object is the provision of novel 25 means for latching and clamping one vertical edge portion of the main door to the door frame or car wall, and providing for the convenient manipulation thereof in closing and opening the main door.

With the foregoing and other objects in 30 view, which will be apparent as the description proceeds, the invention resides in the construction and arrangement of parts hereinafter described and claimed, it being understood that changes can be made within the scope of what is claimed, without departing from the spirit of the invention.

35 The invention is illustrated in the accompanying drawings, wherein:—

Figure 1 is a face view of the improved door construction.

40 Figs. 2 and 3 are enlarged sectional details taken on the respective section lines 2—2 and 3—3 of Fig. 1.

Fig. 4 is a fragmentary elevation showing 45 the lower rear corner of the main door and corresponding parts, portions being broken away.

Figs. 5 and 6 are enlarged sectional views 50 taken on the respective lines 5—5 and 6—6 of Fig. 3.

Fig. 7 is a vertical sectional detail of the 55 lower end portion of the main door showing a modification.

Fig. 8 is a sectional detail showing a 60 further modification.

Fig. 9 is a rear view of the dog or hook 55 of the modified construction shown in Fig. 8.

Fig. 10 is a detail view showing a different form of head for the latch and 60 clamping bolts.

The door frame comprises, as usual, the sill 14, and the posts 15 and 16 at the opposite sides of the door opening, and the main car door 17, as shown, is composed of 65 two layers of wood, although it can be of metal, combination wood and metal or other suitable construction. The door is suspended for longitudinal movement along the exterior of the car wall from a suitable track 18' extending over the doorway or 70 opening.

The door 17 and door frame are provided with means to fit them tightly together for preventing leakage and also excluding the 75 elements from the outside of the car. Thus, a horizontal metallic strip or plate 18 is secured to the outer side of the door 17 along the lower edge or end thereof, and projects downwardly beyond said edge of the door, as seen in Fig. 2, and the lower edge 80 portion of the strip 18 is bent back inwardly and upwardly to form a hook or channel 19 which extends under and behind a depending flange 20 offset outwardly from a rail plate or strip 21 secured to the outer 85 side of the car wall and sill 14, said strip or rail comprising a Z-bar. The offset portion of the strip 21 extends below the door 17, and said door moves over said offset portion, and the hook or channel 19 in engaging 90 under and behind the flange 20 will guide the door 17 and maintain it in position adjacent to the car wall. When the door 17 is in closed position, the lower edge thereof is clamped in place by bolts 22 engaging through the depending portion of the strip 18 and the flange 20, to clamp said strip and flange together and thereby provide a tight joint or fit between the sill and lower edge portion of the door. The 100 bolts 22 are used at spaced points along the strip 18, and in order that said bolts can be readily inserted, the strip has vertical slots 23 while the flange 20 has horizontal slots 23^a, which slots will always 105 register when the door is in closed position, even though there may be a slight variation in the relative position of the door and

guide strip 21, thereby enabling said bolts to be inserted through the intersecting portions of the slots.

A vertical metallic strip or plate 24 is secured to the outer side of the door post 16 (see Fig. 3) and has a portion 25 bent outwardly at an angle to form a stop for the door, against which the forward vertical side edge of the door 17 abuts when said door is slid to closed position. The portion 25 has a flange 26 bent at an angle to overlap said portion of the door, and forming a vertical groove or channel into which said portion of the door moves, to provide a snug fit and to hold the door against the post 16, and prevent leakage.

A vertical Z-bar or strip 31 is secured to the opposite or rear vertical edge of the door and outer side thereof, and has a flange 32 extending from said edge of the door adjacent to the inner side of such door and bearing against a vertical plate or strip 33 which is secured to the inner side of the door at the rear edge thereof. The plate 33 extends across the flange 32 from the rear edge of the door, and has its rear free edge bent inwardly and backwardly to form a hook or channel 35 arranged to move behind the rear edge of a vertical plate or strip 34 secured to the post 15 at the outer side thereof.

The plate 33 and rear edge portion of the door 17 are latched and clamped against the plate 34 and door frame by a vertical series of latching and clamping bolts 36 having nuts 37 screw-threaded thereon at the outer side of the flange 32, and having heads 80 at the inner side of the plate 33 to move behind the plate 34. Each bolt 36 has a reduced oppositely-threaded portion 82 at its outer end on which a lock nut 83 is threaded, to bind against the nut 37 when said nut 37 is tightened, thereby locking the nuts tightly. The portion 82 has a collar 84 on the end thereof, for preventing accidental detachment of the nuts and loss thereof. The shanks of the nuts 36 are movable vertically in vertical slots 81 provided in the flange 32 and plate 33, and the rear edge of the plate 34 has bayonet slots 85 for receiving the bolts 36 when the door 17 is moved to closed position, and the tails 86 of said slots extend downwardly so that the bolts 36 drop down into latching position. The lower edge of the mouth of each slot 85 is inclined, as at 87, to provide a cam against which the corresponding bolt 36 impinges when the door reaches closed position, so that said cam will raise the bolts within said slot 81, and the bolt will drop down into the tail of the slot by gravity. The cam edge 87 is bevelled at this inner side, as at 88, and the shoulder of the bolt head 80 is also bevelled, as at 89, whereby the bevelled shoulder 89 in

contacting with the bevel 88 will cause the head 80 to pass behind the plate 34 without stopping the door. A board 90 is disposed between the post 15 and plate 34, and has a recess or mortise 91 behind each slot 85, to receive the bolt heads 80 behind the plate 34, and the rear edge of the plate 34 projects beyond the board 90 so that the hook 35 can engage behind said plate.

In order that the latch bolts 36 can be operated simultaneously, especially for releasing them from the plate 34, a vertical lift bar 92 extends along the flange 32 at the outer side thereof, and has short vertical slots 93 through which the bolts 36 extend, in order to permit said bolts to adjust themselves vertically slightly relatively to one another. The bar 92 is formed, preferably near the lower end thereof, with an outstanding portion 94 to serve as a handle for raising the bar 92 or to receive the blows of a hammer or other implement to forcibly raise said bar should the latching device stick.

Coming to the auxiliary doors, the main door 17 is provided with openings 38 therein near the upper and lower edges thereof and near the forward vertical edge of the door which moves across the doorway in opening and closing the door. Metallic frames 40 surround the openings 38 at the outer side of the door, and are secured to the door to reinforce it at the openings 38. Each frame 40, which comprises a flat plate, is provided at that edge nearest the opening 38 with an outturned portion 41 surrounding the opening, and having a flange 42 extending at an angle away from the opening, to receive the auxiliary door.

The upper and lower auxiliary doors are designated 43 and 44, respectively, and, as shown, they are duplicate constructions. Each auxiliary door comprises a rectangular cap or panel 45 of sheet metal or other suitable material, having the marginal rim or flange 46 to surround the flange 42 and portion 41 when the cap is fitted against the flange 42, as seen in Fig. 2. The rim or flange 46 overlaps and is secured to a rim member 47 of angular cross section, and said member provides a stiff marginal portion or rim for the door. The rim member 47 is adapted to fit snugly against the frame or plate 40, and can be secured firmly thereto by means of bolts 48 inserted inwardly through apertures in the member 47, frame 40 and door 17, to screw into nuts 49 embedded in the inner surface of the door.

In order to mount the auxiliary doors 43 and 44 for movement to and from the openings 38, arms or straps 51 have their upper ends hingedly connected to the door 17 above the openings 38, and said straps 51 extend across and overlap the caps or pan-

els 45 of the auxiliary doors, and are secured thereto by means of bolts or rivets 58. Vertical arms 50 are hingedly connected to the door 17 above and below the respective auxiliary doors 43 and 44, to swing across the doors toward one another for holding said auxiliary doors closed when said doors are swung downwardly over the openings 38. The arm 50 of the upper door 10 43 is preferably secured thereto to swing therewith.

The hinges for connecting the straps 51 and arms 50 to the doors 17 are all alike. Thus, the hinged ends of said straps and 15 arms have hinge butts 52 and each hinge butt is mounted on a hinge rod or pin 53 having its ends seated in lugs or sockets 54 of plates 55 secured to the door 17. Such hinge plates 55 are arranged in pairs, and 20 the hinge rods 53 being seated in the lugs or sockets 54, will prevent the hinges being opened without removing the plates 55.

The lower arm 50 is preferably secured to the door 17 above the door 44 by means 25 of a bolt 60 engaging inwardly through the arm 50 and door 17 to screw into a nut 61 embedded in the door 17 similar to the nuts 49. The lower auxiliary door 44 can thus be secured in closed position by swinging the 30 arm 50 thereof upwardly and fastening it by the bolt 60.

With the arrangement as shown, the free ends of the two arms 50 project toward one another, and a vertical latch bar 62 is provided for holding said arms when swung 35 across said auxiliary doors, the upper and lower ends of the bar 62 overlapping the free ends of said arms. The bar 62 is secured to horizontal arms or hinge leaves 63' and 63, 40 whereby the bar 62 can be swung away from the arms 50 to release them for opening the auxiliary doors. The arms 63' and 63 and have hinged connections with the door 17 similar to the hinges between the bars 50 and 51 and the door 17. Thus, the hinged end of the arm 63, or 63', has a hinge butt 64 mounted on a hinge rod or pin 65 having its ends seated in lugs or 45 sockets 66 of a pair of plates 67 secured to the door 17.

When the doors 43 and 44 are swung downwardly to closed position and the arms 50 swung across said doors, the bar 62 can be swung against the arms 50, and the arm 63 projects beyond the bar 62 to be secured 55 in place, for holding the latch bar 62 against the arms 50. A bolt 70 is engageable inwardly through the arm 63 and door 17 to screw into a nut 71 embedded in the door 17, whereby to hold the bar 62 before being sealed or after being unsealed.

The arm 63 is held by a seal, whereby all three doors are held closed under a single seal. For this purpose, an ordinary double 60 hasp or sealing link 68 is used, being bent

or offset, if necessary, as seen in Fig. 3. The link 68 has a slot 72 near one end to engage the keeper 69 on the door frame or car wall, whereby a latch pin 73 or seal can be inserted into the keeper, for holding the link 70 68. The link 68 has a slot 74 near its other end, and the arm 63 has means at its free end for the detachable connection of the link 68 when the arm 63 is swung away from the door 17. Thus, the free end of 75 the arm 63 has an offset bill or hook 75 with a finger 76 projecting toward the door 17 to pass through the slot 74, and said finger 76 has a head or enlargement 77. When the arm 63 is swung away from the door 17, link 80 68 can be moved into engagement with or off of the finger 76 over the head or enlargement 77, by turning and manipulating the link to pass laterally over said head, but when the arm 63 is swung against the door 17 and the link 68 engaged with the keeper 69, it is impossible to disconnect the link from the arm 63, because the link is pulled lengthwise into engagement with the finger 76 and cannot be turned or manipulated to move it over the head 77.

In using the door 17, such as when filling the car with grain, sand, or the like, the door 17 is slid to closed position, thereby moving the forward edge against the stop portion 95 25 behind the flange 26, and moving the hook 35 behind the plate 34. During the movement of the door to closed position, the latch bolts 36 will ride up the cam edges 87 so as to drop into the tails 86 of the slots 85; thereby automatically latching the door in closed position, and said bolts 36 are tightened, whereby to clamp the rear edge portion of the door against the door frame. The bolts 22 are then inserted and tightened, 100 to clamp the lower edge portion of the door against the sill, and the door 17 is thus held rigid and secure, to prevent leakage of grain or sand past the edges of said door. The lower auxiliary door 44 is then swung 110 downwardly to closed position, and the lower arm 50 swung upwardly and fastened by the bolt 60, thus holding the lower door 44 to resist outward pressure against the panel or cap 45 thereof. The upper auxiliary door 43 can be swung upwardly and held by catches 43' and the grain, sand or other material can then be run through the upper opening 38 for filling the car. After the car is filled, the upper auxiliary door 115 43 is closed by swinging it downwardly and the arm 50 thereof is swung downwardly with said door. The bar 62 is then swung to overlap the arms 50 of the two auxiliary doors, and is fastened by the bolt 70, the 120 69 and fastened by the usual seal. The link 68 can then be engaged with the keeper 69 and fastened by the usual seal. The doors 17, 43 and 44 are thus maintained in closed position by a single seal, and neither 125 65

of said doors can be opened without breaking the seal.

To start the discharge of grain or other material from the car, the seal is broken and the link 68 disengaged from the keeper 69 and after the bolt 70 is removed, the bar 62 is swung away from the arms 50. The upper auxiliary door 44 can then be opened, for access into the car, and then by removing the bolt 60, the arm 50 can be swung downwardly, thereby releasing the lower auxiliary door 44, and starting the discharge of grain or material through the lower discharge opening 38. The bolts 22 can then be removed and the latch bolts 36 raised with the lift bar 92, so that the door 17 can be slid open, and a shovel can then be used for removing the grain, or enabling the grain to be removed in the customary way.

The door is also useful for other merchandise, and the bolts 22 and 36 hold the door rigidly against the door frame, to resist the jamming and jostling of the merchandise against the door 17, or to prevent leakage of the contents from the car or the entrance of dirt, dust, rain, air or the like, into the car, thus protecting the contents thereof. The single seal will hold all three doors closed, and by releasing the arms 63 and 50, the auxiliary doors can be opened for gaining access to the contents, without opening the door 17, whereby merchandise in the rear of the door 17 can be removed or loosened, should the merchandise jam up against the door. In using the door for ordinary freight, the bolts 48 of the auxiliary doors need not be used, unless it is desired to hold the auxiliary doors tight against the frames 40 to prevent leakage. Any water or moisture which may leak past the upper edges of the auxiliary doors between the upper edges of the frames 40 and rim members 47, will be caught within the channels or troughs formed by the portions 41 and flanges 42 of the frames 40, thereby draining such water around the opposite sides of the openings 38, to drain downwardly past the lower edges of the auxiliary doors, without entering the openings 38.

The auxiliary doors can also have openings therein for purpose of ventilation or examination of the contents of the car.

In order to prevent leakage under the lower rear corner of the door 17, between the lower edge of the door and the offset portion of the rail strip 21, a block 95 of wood or other suitable material is secured on said offset portion of the strip by means of bolts 96 or the like, and said block has a tongue 97 to project under the corner of the door and close the end of the slot between the lower edge of the door and the offset portion of the strip 21. This block 95 can be removed before the door 17 is

slid open, and is readily applied when the door is in closed position.

In Fig. 7 a modified construction is shown for the lower edge portion of the door 17. Thus, the horizontal strip 18" is not secured to the door 17 but extends across the flange 20 of the rail strip 21 at the outer side thereof, and has the hook 19" at its lower edge to move upwardly behind the flange 20. Said strip 18" has vertical slots 23" and the bolts 22 extend through said slots and are carried by the flange 20. Thus, when the bolts 22 are loosened, the strip 18" can be slid upwardly and downwardly, to either cause it to overlap the lower edge portion of the door on the outside thereof as seen in full lines in Fig. 7, to clamp the door against the sill, or said strip 18" can be lowered so to remove it from the door 17, permitting said door to move away from the sill.

In Figs. 8 and 9 there is depicted another device for clamping the lower edge of the door 17 against the sill, and Fig. 8 also shows the Z-rail strip 21 at the lower edge of the sill, so that the lower opening 38 can extend to the sill or floor of the car which arrangement can also be used in the other forms shown. The clamping device shown in Figs. 8 and 9 avoids possible loss of any of the parts, such as as the bolts and nuts, which must be removed with the arrangement shown in the first-described form of construction. In the modified arrangement, there is a spindle 122 extending under the rail 21 and sill 14, and a sleeve 123 is fitted for rotation on the outer terminal of said spindle and has a hook or dog 124 extending to one side and provided with a tooth 125 to engage the plate or strip 18, which is preferably provided with a recess 126 to receive said tooth, it being understood that a number of spindles 122 are used, similar to the bolts 22 hereinbefore described. The outer end of the spindle 122 has a head or member 127 thereon retaining the sleeve 123 on the spindle. Said spindle is mounted for rotary movement and for vertical adjustment in vertical slots 128 in the depending end portions 129 of a plate or bar 130 secured to the lower surface of the sill 14, thereby said spindle is supported from the car body to prevent loss of the spindle and parts carried thereby, and a clamping nut 131 is screw-threaded on the spindle in rear of the outer end portion 129 and can be tightened for drawing the spindle rearwardly or inwardly to engage the hook or dog 124 with the plate 18 and clamp the lower edge of the door against the sill, also clamping the plate 18 against the flange 20.

A lock nut 132 is threaded on the spindle in rear of the nut 131 and by reverse screw thread, whereby the nut 132 can be turned up against the nut 131 to prevent the device

from loosening. A collar 133 is preferably secured on the rear or inner end of the spindle 122 for limiting the outward movement of the spindle in its carrier 130. To open the door, the nuts 132 and 131 are loosened, whereby the spindle 122 and hook or dog 124 can be slid outwardly and such dog then turned downwardly to permit the door 17 to slide open. The clamping device 10 can remain permanently on the car, for the convenient use thereof when needed to secure the lower edge of the door in place, and there is no danger of loss of any of the parts.

15 In Fig. 10 there is shown a modification in the latching and clamping bolts 36, only one of which is shown. Thus, the bolt has an elongated head 80' extended toward one side of the shank of the bolt, whereby said head will hang downwardly by gravity, and said head has a bevel 89' which is maintained in a position to strike the cam edge 87 of the plate 34 when the door is closed. The head 80' in hanging downwardly will 20 keep the bevel 89' in proper position to strike the cam edge 87, and when bolt 36 drops into the tail 86 of the slot 85, the head 80' will prevent the bolt 36 from turning, whereby the nuts can be turned and tightened 25 readily.

Having thus described the invention, what is claimed as new is:—

1. A freight car door construction comprising a door frame having a sill, a door 35 mounted for sliding movement, a rail strip secured to the sill and projecting under the lower edge of the door, said strip having a depending flange below the door, a strip to overlap the lower edge portion of the door 40 and said flange, the last named strip engaging the outer face of the edge portion of the door throughout the width of said door, and means for engaging the last named strip to clamp it against said flange in order to prevent leakage under the lower edge of the door.

2. A freight car door construction comprising a door frame having a sill, a door mounted for sliding movement, a rail strip 50 secured to the sill and projecting under the lower edge of the door, said strip having a depending flange below the door, a strip to overlap the lower edge portion of the door and said flange, the last named strip engaging the outer face of the edge portion of the door throughout the width of said door, and means for engaging the last named strip to clamp it against said flange in order to prevent leakage under the lower edge of the door, the last named strip having its lower edge portion bent inwardly and upwardly 60 to form a hook to engage and move behind said flange for guiding the lower edge of the door along the rail strip.

65 3. A freight car door construction com-

prising a door frame, a door suspended for sliding movement, plates carried by one vertical edge portion of the door and one side member of the door frame to bear against one another when the door is closed, and 70 latching means carried by and movable with one plate for latching and clamping the plates together, the other plate having means for receiving said latching means when the door is slid closed.

4. A freight car door structure including a door frame, a door mounted for sliding movement, plates carried by the door and frame to bear against one another when the door is closed, and latching and clamping 80 bolts movably carried by one plate, the other plate having slots for receiving said bolts when the door is closed to latch the door and enable said plates to be clamped together.

5. A freight car door structure comprising a door frame, a door mounted for sliding movement, plates carried by the door and frame to bear against one another, a latching and clamping member carried by one plate, the other plate having a bayonet 90 slot to receive said member when the door is closed for latching the door and enabling said plates to be clamped together by said member.

6. A freight car door structure comprising a door frame, a door mounted for sliding movement, plates carried by said door and frame to bear against one another when the door is closed, the one plate having a slot, a latching and clamping bolt movable upwardly and downwardly in said slot, and the other plate having a bayonet slot to receive the bolt when the door is closed, for latching the door and enabling said plates to be clamped together by tightening said bolt, the lower edge of the mouth of said bayonet slot being inclined to provide a cam for lifting said bolt when the door is closed, so that the bolt drops into the tail of said bayonet slot.

7. A freight car door structure comprising a door frame, a door mounted for sliding movement, plates carried by said door and frame to bear against one another when the door is closed, the door plate having slot, a latching and clamping bolt movable upwardly and downwardly in said slot and the frame plate having a bayonet slot to receive the bolt when the door is closed, for latching the door and enabling said plates to be clamped together by tightening said bolt, the lower edge of the mouth of said bayonet slot being inclined to provide a cam for lifting said bolt when the door is closed, so that the bolt drops into the tail of said bayonet slot, said bolt having a head to move behind the frame plate, and said head and cam being bevelled so that said head moves behind said frame plate when the door is closed.

8. A freight car door structure comprising a door frame, a door mounted for sliding movement, plates carried by the frame and door to bear against one another when the door is closed, a series of latching and clamping members carried by one plate and movable therein, the other plate having means for receiving said members to latch the door in closed position, said members clamping the plates together when said members are tightened, and means for simultaneously moving said members to and from latching position.

9. A freight car door structure comprising a door frame, a door mounted for sliding movement, plates carried by the frame and door to bear against one another when the door is closed, a series of latching and clamping members mounted for movement in one plate, the other plate having slots for receiving said members when the door is closed, and a bar engaging said members for simultaneously moving them into and out of latching position within said slots.

10. A freight car door structure comprising a door frame, a door mounted for sliding movement, plates carried by said frame and door to bear against one another when

the door is closed, one plate having slots, latching and clamping bolts movable in said slots, the other plate having bayonet slots into which bolts are movable when the door is closed so that the bolts drop into the tails of said bayonet slots to latch the door and permit said plates to be clamped together by the bolts, and a bar having slots receiving said bolts for simultaneously moving said bolts out of said tails of the bayonet slots to unlatching position.

11. A freight car door structure comprising a car wall having a door frame, a door suspended for sliding movement along said wall across said frame, a lower rail strip secured to said wall and extending under the door opening and below said door, a strip to be secured to the aforesaid strip to overlap the lower edge portion of the door and clamp it to the sill of said frame, and a block to be secured on said rail strip having a portion to fit between one lower corner of said door and said rail strip to prevent leakage under said corner of the door.

In testimony whereof I hereunto affix my signature.

JOHN LAYTON GUERRANT.
